HOSE SUPPORTER

Paul Pugniel, Saint-Mande, France

Application April 5, 1935, Serial No. 14,935
In France April 6, 1934

2 Claims. (Cl. 24—245)

The present invention has for its object, as new industrial products:

1.—The hose supporter, in which the button and its base form a single rubber unit, such base being provided with holes extending parallel to its lower face and through which is inserted either the supporting tab itself or means for securing the same.

2.—The rubber strip for the manufacture of buttons and bases for hose supporters, said strip being in the form of a rail and having longitudinal holes bored parallel to its lower face.

By way of example, in the accompanying drawing:

15 Figure 1 is a view in perspective of a rubber strip according to the invention and intended for the manufacture of buttons and bases for hose supporters.

Figure 2 is a front view of a first type of hose supporter according to the present invention.

Figure 3 shows a detail of such hose supporter.

Figure 4 is a section on the line IV—IV of Figure 3.

Figure 5 is a front view of another type of hose supporter according to the invention.

Figure 6 is a section on the line VI—VI of Figure 5.

Figure 7 is a section on the line VII—VII of Figure 6.

30 The rubber strip shown in Figure 1 recalls the structure of a railway rail, in which have been bored holes 1 parallel to the lower face 2 of the base 3.

The hose supporter shown in Figures 1—4 is 35 constituted by a rubber button 4 forming a single unit with its base 3 and obtained by cutting to the desired length the strip shown in Figure 1.

In the holes 1, parallel to the lower face 2 of the base 3 is inserted the iron wire 5 which is 40 bent in order to form a frame. The tab 6 generally constituted by web is carried around one of the sides 5' of the wire 5, then passed under the face 2 of the base 3, then over the other side 5'' of the wire 5 and finally again passed under 45 its own lower face, as shown in Figure 4. Both sides of the tab 6 and the button loop 7 are secured to the attaching link 8 by means of a tubular shackle 9.

The hose support shown in Figures 5 to 7 also 50 comprises a button 4 and a base 3 constituted by a single rubber section, but in this case the wire 5 is omitted and the holes obtained by the die during the manufacture of the strip such as 55 shown in Figure 1, are separated by thin partitions 10 which are easily torn away when the tab 6 is being introduced, i. e. by compressing transversely the base 3. In this way a grooved edge opening is obtained (see Figure 6) in which the tab 6 is directly inserted (see Figure 7). It 60 is to be noted that in all embodiments of the in-

vention, the attaching means is easily inserted in the holes or slot cut in the preformed blank of rubber. In Fig. 3 the wire 5 slides easily in the holes 1; in Fig. 7 the tab 6 slides easily through the slot, as shown.

5

The improved hose supporter thus obtained affords the following advantages:

(a) The button 4 is firmly secured to the tab 6, since it does not comprise metallic parts for clamping the rubber or penetrating by means of projecting parts into the same. Owing to the yielding properties of rubber such attaching means both lack strength.

(b) The hose or the sock is not gripped between two metallic parts which tend to tear it.

(c) Since the tab 6 is firmly held along the whole surface of the base 3 it cannot easily become detached from the base.

(d) The manufacture of the button and of its base is very economical.

15

(e) The tab 6 may be replaced after wearing without it being necessary to completely replace the hose supporter as is the case with the devices in which the tab 6 and the button 4 are constituted by a single unit.

20

(f) The rubber strip shown in Figure 1, enables one to obtain buttons of any given length, and whatever may be such length, their bases will always be bored through and through with holes such as 1 or openings such as 1, 10, thus 30 enabling the button to be secured to the button supporting tabs.

25

What I claim is:

1. A device for supporting hose, socks and like garments comprising a piece of rubber so deformed that the top section is formed as a button and the base contains two holes parallel to the lower surface of said base and parallel to the longitudinal axis thereof, a link, a button loop, a wire deformed rectangularly and having two of its sides passing through said holes in said base, a strap passing freely over the other two sides of the said rectangular wire and under the lower piece of said base and means for attaching said button loop and said strap to said link.

35

2. A device for supporting hose, socks and like garments which comprises a piece of rubber having the configuration of an I-beam wherein the top serves as a button and the bottom as a base, 50 said base having a slot provided therein parallel to the lower surface of said base and in proximity thereto, a button loop, a link, a tab passing freely through said slot, said loop, link, and tab being interconnected, said button loop being constructed and arranged to fit over the button and fit about the center of the I formed by said button.
